United States Patent Office

Des. 210,595
Patented Mar. 26, 1968

210,595

INTERCOMMUNICATIONS UNIT

Robert D. Kahn, Rockville Centre, N.Y., assignor to
Fedtro, Inc., Rockville Centre, N.Y., a corpora-
tion of New York

Filed Dec. 19, 1966, Ser. No. 5,119

Claims priority, application Japan June 21, 1966

Term of patent 14 years

(Cl. D26—14)

FIG. 1.

FIG. 2.

FIG. 3.

FIG. 5.

FIG. 1 is a top plan view of an intercommunications unit showing my new design;

FIG. 2 is a right side elevational view, the left side being substantially a mirror image thereof;

FIG. 3 is a front elevational view;

FIG. 4 shows the contour of the front face taken through section 4—4 of FIG. 1; and

FIG. 5 shows the contour of the front face thereof taken through section 5—5 of FIG. 1.

I claim:

The ornamental design for an intercommunications unit, substantially as shown and described.
